DESIGN FOR A COMBINATION COMPACT AND CIGARETTE CASE

Florence N. Lewis, New York, N. Y.

Application May 5, 1938, Serial No. 77,006

Term of patent 3½ years

To all whom it may concern:

Be it known that I, Florence N. Lewis, a citizen of the United States, residing at New York city, in the county of New York and State of New York, have invented a new, original, and ornamental Design for a Combination Compact and Cigarette Case, of which the following is a specification, reference being had to the accompanying drawing, forming part thereof.

In the drawing:

Fig. 1 is a top perspective view of a combination compact and cigarette case, in closed position, showing my new design;

Fig. 2 is a bottom perspective view thereof.

Fig. 3 is a perspective view similar to Fig. 1 but showing a combination compact and cigarette case in open position.

I claim:—

The ornamental design for a combination compact and cigarette case, as shown and described.

FLORENCE N. LEWIS.
